CLAIM

The ornamental design for a seal/baffle module for humidifier reservoir for positive airway pressure delivery console, as shown and described.

DESCRIPTION

FIG. 1 is a perspective view, from the front, right corner, of a seal/baffle module for humidifier reservoir for positive airway pressure delivery console, according to our new ornamental design;

FIG. 2 is right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is another perspective view thereof.
